UNITED STATES PATENT OFFICE.

GROVER F. COVERDELL, OF COUNCIL BLUFFS, IOWA, ASSIGNOR TO UNDERWOOD TYPE-WRITER COMPANY, OF NEW YORK, N. Y., A CORPORATION OF DELAWARE.

TYPE-WRITING MACHINE.

1,152,934.

Specification of Letters Patent.

Patented Sept. 7, 1915.

Application filed January 20, 1914. Serial No. 313,163.

To all whom it may concern:

Be it known that I, GROVER F. COVERDELL, a citizen of the United States, residing in Council Bluffs, in the county of Pottawattamie and State of Iowa, have invented certain new and useful improvements in Type-Writing Machines, of which the following is a specification.

This invention relates to a feeding device 10 for typewriting machines, whereby envelopes, cards and paper sheets can be successively fed to the platen roll of the machine by merely turning such roll.

The invention has for one of its objects 15 to improve and simplify the construction and operation of devices of this character so as to be comparatively simple and inexpensive to manufacture, reliable and efficient in use, and readily manipulated and 20 adapted for use on any standard typewriter.

Another object of the invention is the provision of an adjustable holder for the different sizes of envelopes, cards and paper.

25 Still another object of the invention is the employment of an improved operating connection between the platen roll of the typewriter and the feed rollers of the attachment.

30 A further feature of the invention is the provision of adjustable guides to receive the envelop or sheet, as it emerges from the platen, to guide it clear of the magazine.

With these objects in view, and others as 35 will appear as the description proceeds, the invention comprises the various novel features of construction and arrangement of parts which will be more fully described hereinafter and set forth with particularity 40 in the claims appended hereto.

In the accompanying drawings, Figure 1 is a front view of this invention detached from the typewriter. Fig. 2 is a rear view of the same, showing the feed rolls and 45 their driving mechanism. Fig. 3 is a side sectional elevation of the same mounted over a platen frame, which is shown diagrammatically. Fig. 4 is a perspective view of one of the guide fingers. Fig. 5 is a perspective view of one of the adjustable end sections of the paper or envelop holder. Fig. 6 is a fragmentary perspective view of 50 one end of the bottom section of the holder. Fig. 7 is a fragmentary perspective view of

the envelop regulator plate. Fig. 8 is a similar view of the paper regulator plate.

Similar reference characters are employed to designate corresponding parts throughout the several views.

Referring to the drawing, A designates the bottom section of the rack or holder for the envelopes, paper or cards, and mounted on this bottom section are adjustable end sections B, whereby the rack can be widened or shortened according to the size of the paper, envelopes or cards to be typewritten. The bottom section A is composed of two guide plates or bars 1 and 2 which are spaced apart to provide a guide passage 3, through which the paper or envelopes are fed, and secured to the ends of these plates or bars are brackets 4, serving to secure the attachment to the carriage 42 of the typewriter, these brackets being of any desired shape or design to suit different makes of typewriting machines. The front guide plate 1 is bent forwardly into a horizontally extending plate portion 5, which has its front edge bent upwardly into a flange 6 extending full length of the bottom section, thereby stiffening the structure and forming a shallow chamber 7 with the receiving regulator plate 8. The rear plate 2 projects above the horizontal plate portion 5 to serve to hold the rearmost sheet of paper, envelop or the like in line with the feed or guide passage 3, and the ends of the plate 2 are bent forwardly to form end walls 9. The end sections B are slidably mounted on the bottom section and each consists of an upwardly extending member 10 which is angular in horizontal cross-section so as to support the ends of the envelopes or sheets of paper held in the attachment. The portions 11 of the members 10 are disposed approximately in the same plane with the rear plate 2 of the bottom section, so that a continuous support for the ends and bottom of the rearmost envelop or sheet will be provided. The portions 12 of the members 10 engage the end edges of the sheets or envelopes to hold them all in even pile and on each member 10 is an inwardly extending finger 13 spaced from the portions 11 to hold the sheets or envelopes in upright position and preventing them from tilting forwardly. On the bottom of each member 10 is a foot extension 14 which rests on the

100
105

horizontal plate 5 of the bottom section A. Each extension 11, as shown in Fig. 5, has an inverted U-shaped lug 15 that has a sliding engagement with the flange 6 of the bottom section of the rack or holder and the outer front portion of the lug has a depending finger piece 16, whereby the end section can be moved inwardly or outwardly. The front edge of the portion 12 of each end section has a recess 17 for engaging a rearwardly bent rib 18 on the flange 6, and the lower extremity 19 of the back portion 11 of each end section projects behind the back plate 2 of the bottom section and is recessed at 20 so as to receive the upper edge of the said back plate 2, and in this manner, the end sections are securely held on the bottom section, although free to slide inwardly or outwardly to change the width of the holder or rack.

The envelops or sheets are fed from the rack by means of spaced rubber faced rollers 21 mounted on a rotary shaft 22, disposed behind the bottom section of the rack and journaled in bearings 23, secured to the ends of the bottom section A and the forward portions of the rollers extend through openings 24 in the back plate 2 of the bottom section. On one end of the shaft is supported a frame 25 composed of spaced plates between which are mounted gear wheels, whereby motion can be transmitted to the shaft 22 by the platen roll 22a. A large gear wheel 26 is journaled in the frame 25 and has a hollow hub 27 through which the platen shaft 27a extends, the hub being rigidly secured to the shaft in any suitable manner. The shaft 22 passes through the frame 25 and has a pinion 28, which is driven from the gear 26, by means of intermediate gears 29. It will be obvious that the turning of the platen will result in the automatic feed of one sheet or envelop at a time from the attachment to the platen. Coöoperating with each feed roller 21 is a gripping roller 31 mounted on the front bar or plate 1 of the bottom section in frictional engagement with its companion feed roller 21. The friction rollers 31 are arranged under the horizontal plate portion 5 of the bottom section A and they engage their respective feed rollers through openings 32 (Fig. 6), in the bar or plate 1. Mounted on the bottom section of the holder or rack is a regulator plate 33, which has its rear edge 34 disposed adjacent the feed rollers, where they project through the openings 24 and this regulator plate is adjustable toward or from the rollers according to the thickness of the envelop, paper or card, so that but one sheet, envelop or card will feed at a time. This plate 33 is disposed over the forward horizontal projecting portion 5 of the bottom section and has its forward edge bent downwardly into a longitudinal flange

35, which is disposed in front of the flange 6 and is secured to the same by bolts 36. On these bolts are resilient washers 37 or equivalent devices, so that by tightening or loosening the nuts of the bolts the rear edge of the regulator plate can be adjusted with respect to the feed rollers. The top surface of the regulator plate shown in Fig. 7, is inclined downwardly and rearwardly so that the lower edges of envelops or sheets 75 will rest on this inclined portion of the pile and thereby the pile will be formed into a comb. The rear edge 34 of the regulator plate is disposed approximately in a horizontal plane passing through the axis of the feed rollers and immediately under this edge 34 are located the friction rollers 31 so that the said friction rollers will take hold of the rearmost card, envelop, or sheet as the latter is moved downwardly off the regulator plate by the feed rollers.

In practice, it has been found that the regulator plate for envelops should be constructed as shown in Fig. 7, with the marginal portion 34 slightly convexed at its top surface, while the regulator plate, (Fig. 8), for paper sheets should have its rear marginal portion slightly concave so as to be disposed more nearly in a radial position with respect to the feed rollers. To insure the proper feeding in of the work-pieces, an arcuate wire 38 is attached at each end to the bolts 36, and bent rearwardly against said work-pieces, to constantly urge the latter onward to the bite of the feed rolls 21 and 31. As the top edge of the work-piece moves away from the platen, after receiving successive lines of impressions from type 39, its side edges are engaged by fingers 40 and guided clear of the magazine through channels 41, formed by bending back portions 42 of the said fingers, as shown in Fig. 4. These fingers are shiftably supported at 43 on the flange 6 of the front guide plate 1, and may be adjusted for variations in the width of the work-pieces.

In operation, the end sections are adjusted inwardly or outwardly according to the width of the envelops, cards or sheets to be typewritten and a proper regulator plate is placed on the bottom section and adjusted back and forth into operative relation with the feed rollers. A pile of envelops, cards, or sheets, as the case may be, is placed in the holder or rack in an approximately vertical position, the ends of the pile being held by the end sections B, while the bottom of the pile rests on the regulator plate with the rearmost envelop, card, or sheet in contact with the feed rollers. The platen roll is now turned so as to cause the co-acting feed and friction rollers of the attachment to remove the rearmost envelop, card or sheet and bring it into coöperative relation with the feeding mechanism of the 130

typewriter, and as the platen is turned step by step in writing the successive lines, the feed rollers of the attachment will be correspondingly turned and eventually grip the next card, envelop or sheet and feed it to the platen. In this manner, the typist can carry on her work with great facility and speed.

From the foregoing description taken in connection with the accompanying drawings, the advantages of the construction and of the method of operation will be readily apparent to those skilled in the art to which the invention relates, and while I have described the principle of operation of the invention, together with the form which I now consider to be the best embodiment thereof, I desire to have it understood that the form shown is merely illustrative and that such changes may be made when desired as are within the scope of the claims.

Variations may be resorted to within the scope of the invention, and portions of the improvements may be used without others.

Having thus described my invention, I claim:

1. The combination, with a rotary platen, of a work-piece receptacle comprising a bottom section having a feed passage leading therefrom to the introductory side of the platen, a regulator mounted upon said bottom section for supporting the lower edges of the work-pieces, and vertical end sections for supporting the side edges of said work-pieces adjustably mounted upon said bottom section for movement toward or from each other, to conform to the width of the work-pieces; and feeding means mounted on said bottom section and projecting into said passage, to engage said work-pieces, said regulator being adjustable toward and from said feeding means to permit only a single work-piece at a time to be fed thereby through the passage.

2. The combination, with a rotary platen, of a work-piece receptacle comprising a bottom section having a feed passage leading therefrom to the introductory side of the platen, a regulator mounted upon said bottom section for supporting the lower edges of the work-pieces, and vertical end sections for supporting the side edges of said work-pieces adjustably mounted upon said bottom section for movement toward or from each other, to conform to the width of the work-pieces; and coacting feed and friction rollers mounted on said bottom section and projecting into said passage from opposite sides thereof, to engage said work-pieces, said regulator being adjustable toward and from said feed rollers to permit only a single work-piece at a time to be fed thereby through the passage.

3. The combination, with a rotary platen, of a work-piece receptacle comprising a bot-

tom section having a feed passage leading therefrom to the introductory side of the platen, said section consisting of front and rear plates having adjacent portions thereof bent downwardly and spaced apart to form said passage, a regulator mounted upon said bottom section for supporting the lower edges of the work-pieces, and vertical end sections mounted upon said bottom section for supporting the side edges of said work-pieces; feed rollers projecting from the passage-forming portion of one of said plates into said passage, to engage said work-pieces; and friction rollers projecting into said passage from the passage-forming portion of the other plate, to coact with said feed rolls, said regulator being adjustable toward and from said feed rollers to permit only a single work-piece at a time to be fed thereby through the passage.

4. The combination, with a rotary platen, of a work-piece receptacle comprising a bottom section having a feed passage leading therefrom to the introductory side of the platen, said section consisting of front and rear plates having adjacent portions thereof bent downwardly and spaced apart to form said passage, a regulator mounted upon said bottom section for supporting the lower edges of the work-pieces, and vertical end sections for supporting the side edges of said work-pieces adjustably mounted upon said bottom section for movement toward and from each other, to conform to the width of the work-pieces; feed rollers projecting from the passage-forming portion of one of said plates into said passage, to engage said work-pieces; and friction rollers projecting into said passage from the passage-forming portion of the other plate to coact with said feed rollers, said regulator being adjustable toward and from said feed rollers to permit only a single work-piece at a time to be fed thereby through the passage.

5. An apparatus of the class described, comprising a bottom section composed of two plates spaced apart to form a passage between them; feed rollers mounted on the said section, means for rotating the rollers, a regulator plate mounted on the said section in co-operative relation with the feed rollers, adjustable end sections mounted on the bottom section, and devices movable under the regulator plate for adjusting the end sections.

6. An apparatus of the class described, comprising a bottom section composed of a rear plate having openings and a front plate having openings alining with those in the rear plate, said plates being spaced apart to form a feed passage; feed rollers mounted behind the rear plate and extending through the openings thereof and disposed in tangential relation to the feed passage; friction rollers mounted on the front plate and ex-

tending through the openings thereof in co-acting relation with the feed rollers; a regulator carried by the front plate and adjustable toward and from the feed rollers; and 5 end sections mounted on the bottom section to coöperate therewith for supporting a pile of sheets or the like on the regulator.

7. An apparatus of the class described, comprising a bottom section composed of a 10 rear plate having openings and a front plate having openings alining with those in the rear plate, said plates being spaced apart to form a feed passage; feed rollers mounted behind the rear plate and extending through 15 the openings thereof and disposed in tangential relation to the feed passage; friction rollers mounted on the front plate and extending through the openings thereof in co-acting relation with the feed rollers; a regulator 20 carried by the front plate and adjustable toward and from the feed rollers; and adjustable end sections mounted on the bottom section, each end section consisting of an upwardly extending member of angular 25 cross-section and having means for connecting the bottom of the member with the bottom section.

8. An apparatus of the class described, comprising a bottom section composed of a 30 rear plate having openings and a front plate having openings alining with those in the rear plate, said plates being spaced apart to form a feed passage; feed rollers mounted behind the rear plate and extending through 35 the openings thereof and disposed in tangential relation to the feed passage; friction rollers mounted on the front plate and extending through the openings thereof in co-acting relation with the feed rollers; a regulator 40 carried by the front plate and adjustable toward and from the feed rollers; adjustable end sections mounted on the bottom section, each end section consisting of an upwardly extending member of angular cross- 45 section and having means for connecting the bottom of the member with the bottom section; and devices connected with the end sections and disposed under the regulator for adjusting the position of the end sections. 50

9. An apparatus of the class described, comprising a bottom section having a feed passage leading therefrom; rollers mounted on said bottom section for feeding a work-piece through said passage; means for rotating said rollers; adjustable end sections mounted on said bottom section; and devices movable beneath the bottom section for adjusting the end sections. 55

10. The combination of a work-piece receptacle comprising a bottom section provided with an upstanding, longitudinal flange, and with a feed passage, and vertical end sections adjustably mounted upon said bottom section for movement toward and

from each other, to conform to the width of the work-pieces, said end sections being provided with lugs slidably embracing said flange; and means mounted upon said bottom section for feeding the work-pieces 70 through said passage.

11. The combination of a work-piece receptacle comprising a bottom section provided with an upstanding, longitudinal flange, and with a feed passage, and vertical 75 end sections adjustably mounted upon said bottom section for movement toward and from each other, to conform to the width of the work-pieces, said end sections being provided with lugs slidably embracing said flange and projecting below said bottom section to adjust said end sections; and means mounted upon said bottom section for feeding the work-pieces through said passage.

12. The combination of a work-piece receptacle comprising a bottom section provided with an upstanding, longitudinal flange, and with a feed passage, vertical end sections adjustably mounted upon said bottom section for movement toward and from each other to conform to the width of the work-pieces, and a regulator plate for supporting the lower edges of the work-pieces inclined at one side toward said passage and projecting at the other side over said flange 95 and then downwardly adjacent the same; means projecting into said passage for engaging the work-pieces and feeding them therethrough; and adjusting means connecting said flange and the projecting side of 100 said regulator plate, for moving the latter toward or from said feeding means.

13. The combination of a work-piece receptacle comprising a bottom section provided with an upstanding, longitudinal flange, and with a feed passage, vertical end sections adjustably mounted upon said bottom section for movement toward and from each other to conform to the width of the work-pieces, said end sections being provided with lugs which slidably straddle said flange and project below the same to adjust the end sections, and a regulator plate for supporting the lower edges of the work-pieces inclined at one side toward said passage and projecting at the other side over said flange and lugs, and then downwardly adjacent the same; means projecting into said passage for engaging the work-pieces, and feeding them therethrough; and adjusting means connecting said flange and the projecting side of said regulator plate, for moving the latter toward or from said feeding means. 110

14. The combination, with a rotary platen; 125 of a work-piece receptacle comprising a bottom section for supporting the lower edges of the work-pieces having a feed passage located over the rear side of the platen, and vertical end sections for supporting the side 130

edges of said work-pieces; means mounted on said bottom section and projecting into said passage for engaging said work-pieces and feeding them therethrough to said 5 platen; and depending guide fingers located in front of said platen for engaging the printed work-pieces as they move upwardly away from the platen, said end sections and said guide fingers being adjustably connected with said bottom section for movement toward and from each other, to conform to the width of the work-pieces.

15. The combination, with a rotary platen, of a work-piece receptacle comprising a bottom section for supporting the lower edges 15 of the work-pieces provided at its rear with a passage located over the introductory side of the platen, and at its front with an up-standing, longitudinal flange, and vertical 20 end pieces for supporting the side edges of said work-pieces; means mounted on said bottom section and projecting into said passage for engaging said work-pieces and feeding them therethrough to said platen; and 25 depending guide fingers located in front of said platen for engaging the printed work-pieces as they move upwardly away from the platen, said end sections and said guide fingers having supporting portions slidably

embracing said flange, to permit movement thereof toward and from each other to conform to the width of the work-pieces.

16. The combination, with a rotary platen, of a work-piece receptacle comprising a bottom section for supporting the lower edges 30 of the work-pieces having a feed passage located over the rear side of the platen, and vertical end sections for supporting the side edges of said work-pieces; means mounted on said bottom section and projecting into 35 said passage for engaging said work-pieces and feeding them therethrough to said platen; and depending guide fingers located in front of said platen for engaging the printed work-pieces as they move upwardly 40 away from the platen, said guide fingers being bent to form channels adapted to receive the opposite marginal portions of said work-pieces and guide them clear of said receptacle, and being adjustably connected with 45 said bottom section for movement toward and from each other to conform to the width of the work-pieces.
